UNITED STATES PATENT OFFICE.

CARL HOFFMAN, OF ALLENTOWN, PENNSYLVANIA.

LATCH AND LOCK FOR DOORS.

Application filed October 9, 1922. Serial No. 593,285.

To all whom it may concern:

Be it known that I, CARL HOFFMAN, a citizen of the United States, residing at Allentown, in the county of Lehigh and State of Pennsylvania, have invented certain new and useful Improvements in Latches and Locks for Doors; and I do hereby declare the following to be a full, clear, and exact description of the invention, such as will enable others skilled in the art to which it appertains to make and use the same.

My invention relates to locks, and the object of the invention is to provide a simple latch and lock mechanism with improved means for effecting the latching and locking operations of the parts, and one wherein the arrangement of the elements affords a maximum of security both as a latch and a lock.

In the drawings, Figure 1 is a view in side elevation showing the parts in latching position, the cover plate of the lock case being removed and portions of the door and its casting being shown in section. Figure 2 is a similar view but with the lock protracted. Figure 3 is a cross sectional view on line 3—3, Figure 1. Figure 4 is a vertical sectional view on line 4—4, Figure 1. Figure 5 is a sectional view on line 5—5 of Figure 4. Figure 6 is an elevation showing the dead bolt protracted. Figure 7 is a cross sectional view on line 7—7, Figure 1. Figure 8 is a perspective view of the lock case with the cover plate removed, and Figures 9 and 10 are similar views of the latch and the bolt, respectively.

The elements of my improved lock are assembled in the usual lock case 1 composed of edge plate, bed plate and cover, each provided with the necessary openings and spacing posts. The latch is shown at 2 and is formed integrally with a skeleton plate 3, an enlargement 4 at the other end of the plate serving as the means against which wings 5 of a knob operated spindle 6 bear in moving the plate with its latch against the tension of spring 7. The enlargement 4 is grooved as at 8 to work over the guide 9 of the lock case. Depending from the lower side of the skeleton frame is a lip 10 adapted for co-operation with a stop pin 12 to prevent movement of the latch.

At 20 I have shown a tumbler controlled lock adapted for manipulation by a key engaging talons 21 and 22, two turns of the key being necessary to set the lock in fully

protracted position, the first turn merely moving it to the position indicated by dotted line A, Figure 2. The bolt has a slot 23 which serves to guide it over a lug 24 of the lock case, and it is also provided with a stud 25 which engages one or the other of three cut outs 26 of the tumbler 27 by which it is held in its various positions. A spring 28 insures engagement of the cut out portions of the tumbler with a stud 25 of the lock. The tumbler is pivoted on the post 29, and has a semi-circular recess 30 which is designed to receive the stop pin 12 when the parts are in the position shown in Figure 1. Movement of the tumbler for engagement with stud 25 is effected by a key turning against the lower curved edge of the tumbler. The lock bolt 20 has a lever pivotally mounted thereon and which serves to hold the latch in protracted position when the lock bolt is extended its full distance. The long arm 40 of this lever at its upper end is fitted between two laterally projecting pins 41 of the latch and in the position of the parts shown in Figure 1 in no way interferes with manipulation of the latch. As shown in Figure 2, however, when the lock bolt is protracted to its full extent it carries the lever to a point where its lower short arm 42 bears against the edge plate of the lock case so that turning of the latch 2 will be impossible, pressure to move the latch inwardly being met with the resistance against the lever of the edge plate. It will be seen that in order to dislodge the parts from this position key manipulation is necessary, the key first moving the tumbler and then the lock bolt to its half-way position and on further turning to its fully retracted position. The latch is then free to move through actuation of the winged spindle 6. It is manifest that if desired the stop pin 12 may be pushed into the path of the latch lip 10 and the tumbler 27 to prevent actuation of the latch and movement of the tumbler. As a further means for preventing operation of the parts I provide a dead bolt 50 suitably guided in its sliding movements by a lug 51 of the lock case and a spring 52 on the cover plate which bears down against and holds the bolt in position. This bolt has an upstanding arm 53 which when the bolt is shot partly closes the key opening, thus preventing insertion of a key. The bolt is operated by a permanently fixed key 54.

In the assembling of the parts I find that most satisfactory results are obtained by forming the wings 5 with a hub having a squared bore to receive the squared portion 5 of the spindle 6, the inner knob being screwed to the spindle and fixed by a cotter 60 which is then protected by a collar 61 secured to the outer plate.

The advantages of my invention will be 10 apparent to those skilled in the art. It will be noted that I have provided a simple mechanism whereby a door may be readily latched and when once locked against operation other than by a key or where it can be 15 so locked that there can be no key operation without first moving parts under the control of a person within doors.

I claim as my invention:

1. A latch and lock mechanism including 20 a lock case, a spindle operated spring controlled latch, a tumbler controlled lock bolt, a tumbler for the latter, a common means for independently engaging and locking both latch and tumbler, and a lever pivoted 25 on said lock bolt and engaging said latch whereby the latter will be held against movement when said lock bolt is protracted.

2. A latch and lock mechanism including 30 a lock case, a spindle operated spring controlled latch, a tumbler controlled lock bolt, a tumbler for the latter, a common means for independently engaging and locking both latch and tumbler, and a two arm lever pivoted on said lock bolt and having one arm

in engagement with said latch and the other 35 adapted to contact with the lock case whereby the latch will be held against movement when said lock bolt is protracted.

3. A latch and lock mechanism including 40 a lock case, a spindle operated spring controlled latch, a key actuated tumbler controlled lock bolt, a lever pivoted on said lock bolt and engaging said latch whereby the latter will be held against movement when said lock bolt is protracted, and a transversely movable pin engageable with said latch and the tumbler of said lock bolt for 45 preventing operation of said key controlled lock bolt to withdraw said lever.

4. A latch and lock mechanism includ- 50 ing a lock case, a spindle operated spring controlled latch, said latch having a depending portion, a key controlled lock bolt, a spring actuated tumbler cooperating with said lock bolt to hold it in various positions, 55 means carried by said lock bolt and engaging said latch whereby the latter will be held against movement when said lock bolt is protracted, and a stop pin adapted to be projected into the path of said depending portion of said latch and said spring actuated tumbler to prevent operation of said latch and movement of said lock bolt to 60 withdraw said holding means.

In testimony whereof I have signed this 65 specification.

CARL HOFFMAN.
